(57) **CLAIM**

The ornamental design for a control panel, substantially as shown and described.

DESCRIPTION

FIG. 1 is a front perspective view of an embodiment of a design for a control panel, which may be used in a security system, a home automation system, etc.;
FIG. 2 is a front view of the embodiment of the design for the control panel shown in FIG. 1;
FIG. 3 is a first side view of the embodiment of the design for the control panel shown in FIG. 1;
FIG. 4 is a second side view of the embodiment of the design for the control panel shown in FIG. 1;
FIG. 5 is a top view of the embodiment of the design for the control panel shown in FIG. 1;
FIG. 6 is a bottom view of the embodiment of the design for the control panel shown in FIG. 1; and,
FIG. 7 is a rear view of the embodiment of the design for the control panel shown in FIG. 1.
The broken line showing of the control panel is for illustrative purposes only and forms no part of the claimed design.
